UNITED STATES PATENT OFFICE

2,671,472

CIRCULAR LOOM

Robert Norrie Low, Dundee, Scotland, and Jean Catry, Flixecourt, France, assignors to Fairwest (U. K.) Limited, London, England, a British company

Application June 20, 1952, Serial No. 294,533

Claims priority, application Great Britain June 29, 1951

7 Claims. (Cl. 139—13)

1

This invention relates to shedding mechanisms for circular looms and has for its object to provide improved means for actuating the healds whereby the healds or group of healds may not only be controlled individually but the whole of the healds may be caused to move towards one of their extreme positions, so that the warp threads uncover the shuttles, when required.

According to the invention, each heald or group of healds in the shedding mechanism of a circular loom is connected with a pair of hooks in such manner that the movement of the one hook causes the heald or group of healds to move towards one extreme position whilst movement of the other causes the heald or group of healds to move towards the other extreme position, said hooks being adapted to be engaged at will and actuated by a knife adapted to be reciprocated in conformity with the movement of the shuttles, means being provided for determining which of said hooks shall be engageable by said knife at any instant.

One form of the invention will be described with reference to the accompanying drawing, which is a partially diagrammatic elevation. As shown in the drawings a slideable rod 8 which carries a heald 11 is formed with a longitudinally extending toothed rack which is engaged by a toothed quadrant 7 carried by a sprocket wheel 6 over which extends a chain 5 bearing a hook 3 and 4 on each of its dependent ends, the points of the two hooks being towards each other and the arrangement being such that a downward movement of hook 4 will cause an upward movement of the heald 11 whilst the downward movement of hook 3 will cause a downward movement of the heald 11.

Intermediately of the two hooks 3 and 4 and in their common vertical plane extends a vertical spindle 2 mounted so as to be slideable longitudinally under the combined actions of an upwardly acting spring 12 and an annular face cam 1 in engagement with roller or bowl 13 mounted on said rod 2. The annular face cam 1 is arranged coaxially of the loom and rotates at the same speed as the shuttles.

The vertically slideable spindle 2 carries on its upper end a double edged knife 14, the ends of which are capable of engaging with the two hooks 3 and 4 alternatively.

The stems of the two hooks 3 and 4 extend slideably through holes in a horizontally slideable plate or bar 15 whereby they are held spaced apart by a distance slightly greater than the distance between the two ends of the knife 14. The slide plate 15 is normally influenced in one direction by a spring 10 and is adapted to be moved in the

2

other direction against said influence, by means of an electro-magnet or solenoid 9 or, if desired, by a pneumatic or mechanical device. The arrangement is such that movement of the slide plate 15 causes the hooks 3 and 4 to be moved the one into, and the other out of, the path of its respective knife-end, the preferred arrangement being that the spring 10 tends to move into the path of its knife-end the hook 3, the descent of which will cause the descent of the warp threads.

During normal operation of the loom, the knife-carrying, vertically slideable, spindle 2 is caused by the annular cam 1 to reciprocate in conformity with the movement of the shuttles and, during its downward movements, its knife ends will engage whichever of the hooks has been moved into its path. If no change has been made in the lateral position of the hooks, the knife-carrying spindle 2 will move idly.

20 By suitably arranging the sequence of movements of the pair of hooks 3 and 4 in relation to the movements of the knife-carrying spindles 2, the pattern of the cloth woven by the loom may be varied. If all the horizontally slideable plates 15 controlling the lateral positions of the hooks 3 and 4 are released to the action of their controlling springs 10 the whole of the warp threads are dropped to expose the shuttles, this latter action being particularly easy in the case of electromagnetic operation because the dropping of the warp threads may be effected by merely breaking the electrical circuit.

We claim:

1. Sheding mechanism for a circular loom, comprising a heald adapted to be moved into two extreme positions, a rotary member, a pair of hooks connected to said rotary member on opposite sides of its axis, means operative by rotation of said rotary member to cause reciprocatory movement of the heald, a hook-operating member engageable with either of said hooks to transmit movement thereto, and means for causing one or the other of said hooks to engage said hook-operating member.

2. Sheding mechanism for a circular loom, comprising a heald adapted to be moved into two extreme positions, a rotary member, a pair of hooks connected to said rotary member on opposite sides of its axis, means operative by rotation of said rotary member to cause reciprocatory movement of the heald, a reciprocating knife engageable with either of said hooks to transmit movement thereto, and means for causing one or the other of said hooks to engage said reciprocating knife.

3. Sheding mechanism as defined in claim 2,

including at least one electrical solenoid adapted to control the sequence of engagements between said hooks and said reciprocating knife.

4. Sheding mechanism for a circular loom, comprising a heald adapted to be moved into two extreme positions, a rotary member, a pair of hooks connected to said rotary member on opposite sides of its axis, an extension on the heald having a toothed surface thereon, an arcuate toothed surface on said rotary member engaging said toothed surface on said extension whereby rotation of said rotary member causes reciprocatory movement of the heald, a hook-operating member engageable with either of said hooks to transmit movement thereto, and means for causing one or the other of said hooks to engage said hook-operating member.

5. Sheding mechanism for a circular loom, comprising a heald adapted to be moved into two extreme positions, a rotary member, a pair of hooks connected to said rotary member on opposite sides of its axis, an extension on the heald, a toothed surface on said extension, an arcuate toothed surface on said rotary member engaging said toothed surface on said extension whereby rotation of said rotary member causes reciprocatory movement of the heald, a reciprocating knife engageable with either of said hooks to transmit movement thereto, and means for causing one or the other of said hooks to engage said reciprocating knife.

6. Sheding mechanism for a circular loom, comprising a heald adapted to be moved into two extreme positions, a rotary member, a pair of hooks connected to said rotary member on opposite sides of its axis, means operative by rota-

tion of said rotary member to cause reciprocatory movement of the heald, a reciprocating knife engageable with either of said hooks to transmit movement thereto, means for causing one or the other of said hooks to engage said reciprocating knife, an annular cam arranged coaxially of the loom, means for transmitting motion from said annular cam to said reciprocating knife, and means for causing one or the other of said hooks to engage said reciprocating knife.

7. Sheding mechanism for a circular loom, comprising a heald adapted to be moved into two extreme positions, a rotary member, a pair of hooks connected to said rotary member on opposite sides of its axis, an extension on the heald, a toothed surface on said extension, an arcuate toothed surface on said rotary member engaging said toothed surface on said extension whereby rotation of said rotary member causes reciprocatory movement of the heald, a reciprocating knife engageable with either of said hooks to transmit movement thereto, an annular cam arranged coaxially of the loom, means whereby said annular cam transmits motion to said reciprocating knife, and means for causing one or the other of said hooks to engage said reciprocating knife.
